UNITED STATES PATENT OFFICE.

ORRELL ASHTON, OF SWAMPSOFT, MASSACHUSETTS, ASSIGNOR TO UNITED SHOE MACHINERY COMPANY, OF PATERSON, NEW JERSEY, A CORPORATION OF NEW JERSEY.

SHOE-SHAPING MACHINE.

1,175,217.

Specification of Letters Patent. Patented Mar. 14, 1916.

Application filed April 9, 1915. Serial No. 20,213.

To all whom it may concern:

Be it known that I, ORRELL ASHTON, a citizen of the United States, residing at Swampscott, in the county of Essex and 5 State of Massachusetts, have invented certain Improvements in Shoe-Shaping Machines, of which the following description, in connection with the accompanying drawings, is a specification, like reference characters 10 on the drawings indicating like parts in the several figures.

This invention relates to machines for use in shaping shoes and is herein shown as embodied in mechanism which is particularly 15 useful for shaping turn shoes although not necessarily restricted to use upon shoes of this particular type.

In the manufacture of turn shoes, in which the upper is sewed directly to the 20 single sole while the parts are inside out and the shoe is then turned and relasted, both the upper and the sole after relasting are found to be in a more or less wrinkled and distorted condition. This is particularly 25 noticeable at the sides of the upper and at the projecting edge portion of the sole and on the bottom of the sole over the line of sole attaching stitches. It is necessary, therefore, after the relasting of the shoe, to 30 conform the upper to the last and to shape the sole. The operation of shaping the upper is usually effected by the use of means engaging the side of the shoe from the welt 35 crease upwardly and operated to beat or rub the upper to conform it to the shape of the last. Because of the relatively thin and yielding character of the sole of a turn shoe and the fact that at this stage in the manufacture of the shoe the sole is in a damp 40 and pliable condition, it is important during the operation of shaping the upper to guard against bending the projecting edge portion of the sole downwardly away from the upper and opening the welt crease in 45 such manner as to show the sole attaching stitches; and because of the above-mentioned character and condition of the sole it has been found advantageous also in shaping the projecting edge portion to operate upon 50 both sides of the sole simultaneously.

An important object of this invention accordingly is to provide improved mechanism

for use in shaping the upper and portions of the sole of a turn shoe constructed and arranged with particular reference to the 55 above described conditions which are met with in the manufacture of such shoes.

To the above and other ends a feature of the invention consists in a novel combination and arrangement of means for engaging 60 and beating the side of a shoe from the welt crease upwardly and means for supporting the projecting edge portion of the sole during the beating operation. As herein shown this organization comprises a beating tool 65 shaped for engagement with the side of a shoe from the welt crease upwardly, means for imparting substantially right line movements to the tool in parallel relation to the plane of the sole to cause the tool to beat 70 the shoe, and a support arranged for continuous engagement with the bottom face of the projecting edge portion of the sole to preserve the contour of the shoe bottom during the beating operation. 75

A further feature of the invention consists in a novel arrangement of mechanism for shaping the projecting edge portion of the sole of a shoe comprising, in the preferred embodiment illustrated, a pair of 80 tools arranged to press yieldingly upon opposite faces of the edge portion of the sole and suitably operated to cause them to rub said faces inwardly substantially at right angles to the sole edge. As herein shown 85 and described the means for rubbing the upper face of the projecting portion of the sole is a portion of a beating tool which is shaped for engagement with the upper from the welt crease upwardly, and the tool for 90 rubbing the lower face of the sole is suitably extended to engage that portion of the sole in which the sole attaching stitches are located and is arranged also to support the 95 edge portion of the sole during the beating and rubbing operations.

The above and other features of the invention, including certain details of construction and combinations of parts, will now be described with reference to the accompanying drawings and pointed out in the 100 claims.

In the drawings, Figure 1 is an end view of mechanism embodying a preferred form

of the invention, and Fig. 2 is an enlarged perspective view of a portion of the mechanism shown in Fig. 1.

It will be understood that the mechanism shown may be mounted upon a suitable base for use as a separate machine for operating upon shoes, or may form a part of a machine which includes other shoe treating instrumentalities.

10 The illustrated mechanism includes features of a shoe shaping device which is described and claimed in my prior application for Letters Patent, Serial No. 806,325, filed Dec. 12, 1915, and the invention presents, in one aspect, an improvement in the construction of the prior device. It will be apparent, however, from a consideration of the following detailed description that although there are practical advantages in 15 this construction and arrangement, the present invention in many of its features is not limited to this particular embodiment.

The operating means for the shoe treating tools comprises a tool carrier in the form of 20 a lever 2 which is pivoted at 4 and is oscillated through the engagement with its arm 6 of a cam 8 on a shaft 10 driven, in the arrangement shown, by a belt 12. The lever 2 serves not only as a carrier for tools which 25 are formed, as will be subsequently described, for shaping the sides of the upper and the projecting edge portion of the sole of a shoe, but in the construction shown is formed also with a beating face 14 for use 30 in shaping the bottom of the sole at the shank. The lever is maintained normally, by means of a spring pressed plunger 16, in an idle or inoperative position with its arm 6 outside the path of movement of the 35 cam 8, and the lever is moved into position to be operated by the cam through pressure of a shoe against one or another of the 40 shoe treating tools. At the sides of that portion of the lever upon which the face 14 is formed are shoe supports 18 upon which to position the sole of the shoe so as to prevent the shoe from pressing the tool to the limit of backward movement which would 45 be permitted by the operating means and thus insure a sudden positive pressure of the tool upon the sole when the cam 8 comes 50 into engagement with the lever. Since a greater range of movement of the lever is desirable for shaping the shank portion of the sole than for treating other portions of the shoe, the machine is provided with a pivoted stop 20 which may be turned into the dotted line position to permit a relatively wide range of oscillation of the lever 55 when the shank beating face 14 is to be used and has a shoulder 22 which, as illustrated, limits the backward movement of the lever when other tools are in use so as to prevent the lever from being moved so far by the 60 cam 8. A spring stop 24 engaging in 65

notches formed in the member 20 serves to retain said member in either position of adjustment. For limiting the forward throw of the lever and avoiding danger of breakage of the arm 6 when a shoe is suddenly removed from a tool, the machine is provided with a spring held stop 26.

The parts thus far specifically described are constructed in substantially the same manner as in the device of my prior application previously referred to and require no further description.

In the illustrated construction the lever 2 is formed with a rounded shank portion 28 upon which is mounted, beyond the ends of the shoe supports 18, a tool head 30. Secured upon one side of this head is a beating tool 32 shaped for engagement with the side of a shoe from the welt crease upwardly in the shank portion of the shoe. The head, on the opposite side, has flanges 34 upon which is slidably mounted a tool 36 shaped for engagement with the side of a shoe from the welt crease upwardly at the forepart and having an end surface 38 formed for engagement with the upper face of the projecting edge portion of the sole of the shoe during the beating of the upper. The head 30 is formed also to provide a tool 40 which projects over the tool 36 and has a face opposite to the face 38 of the latter tool for engagement with the bottom of the shoe sole. The tool head 30 may be turned about the shank 28 of the lever to bring either the tool 32 or the tools on the opposite side of the head into position to operate upon a shoe, and it has in one end a slot which cooperates with a pin 42 to retain the head in either position of adjustment. A spring 44 encircling the shank 28 at the other end of the head 30 tends to maintain the head in engagement with the pin 42. Between the end of this spring and the head 30 is a plate 46 which is loosely mounted on the shank 28 so as to permit it to tip with reference to the shank and is extended to engage under the lower end of the tool 36, the plate having lugs 48 for maintaining it in proper relation to the head. The tool 36 is thus maintained normally, by means of the spring 44 and the plate 46, in such a position that the opposite faces of the tools 36 and 40 are separated a distance less than the thickness of a shoe sole, the face on the tool 40 being curved as shown to permit the sole to be readily inserted between the tools in the position illustrated in Fig. 1. When the sole is in this position the plate 46 is slightly tipped, as shown, in opposition to the force of the spring 44, and the tools 36 and 40 are thus caused to engage the opposite faces of the sole with yielding pressure. The tool 40, as shown in Fig. 1, is suitably extended to engage that portion of the sole in which the sole attaching stitches are located.

In the operation of the device for treating the upper and the projecting edge portion of the sole of a shoe, the stop 20 will be positioned as shown to limit the extent 5 of oscillation of the lever, and with a shoe presented as illustrated and pressed against the tool to bring the lever into position to be operated by the cam 8, the tool 36 will beat and shape the upper in and adjacent 10 to the welt crease and at the same time will rub the upper face of the projecting edge portion of the sole. The tool 40 also will rub in a similar manner the lower face of the sole transversely of the line of sole attaching 15 stitches and will smooth down that portion of the sole in which the stitches are located and coöperate with the tool 36 to straighten and shape the sole at the edge. The pressure of the spring 44 serves to 20 maintain both tools in effective rubbing engagement with the sole. Either of the tools 36 or 40 serves, it will be observed, as a support for the sole during its treatment by the other tool. In connection with the beating 25 operation of the tool 36 the tool 40 thus has an important function in preventing the edge of the sole from being bent downwardly away from the upper in such manner as to strain the stitches. In view of the 30 relatively small range of movement of the lever 2 and the distance of the tools from the fulcrum point, it will be apparent that substantially right line movements are imparted to the tools. If it is desired to beat 35 the upper of a shoe in the shank portion, the tool head 30 may be moved downward on the member 28 to free the pin 42 from the slot in the head, and then turned half way around to bring the tool 32 at the front of 40 the device, the pin 42 again coöoperating with the slot to retain the head in this position. If the sole is to be beaten at the shank the stop 20 will be turned down into the dotted line position and the shoe 45 pressed against the face 14 of the lever and against the supports 18 in the manner more fully explained in my prior application to which reference has been made.

It should be understood that the expression "edge portion of the sole" as used herein comprehends whatever materials are included between the upper and lower faces of the margin of the bottom of a turn shoe or shoe of other type in the manufacture of 50 which the machine may be used, and that the term "welt crease" refers generically to the crease between the upper of a shoe and the projecting portion of the shoe bottom.

Having described the invention, what I 55 claim as new and desire to secure by Letters Patent of the United States is:—

1. A machine of the class described having, in combination, means for continuously engaging the projecting edge portion of the 60 sole of a shoe on opposite sides, and means

for imparting to said engaging means approximately right line movements directed inwardly from the edge of the sole to cause said means to rub the upper and lower faces of said projecting portion of the sole. 70

2. A machine of the class described having, in combination, a pair of rubbing tools relatively movable to receive the projecting edge portion of the sole of a shoe between them, yielding means for causing said tools 75 to press upon the sole, and means for imparting to the tools in unison approximately right line movements to rub the sole.

3. A machine for operating upon turn shoes having, in combination, a pair of rubbing tools arranged to engage respectively the upper and lower faces of the projecting edge portion of the sole of a shoe, means for causing the tools to press upon said faces, the tool which operates upon the lower face of the sole being suitably extended to engage simultaneously with the edge portion that portion of the sole in which the sole attaching stitches are located, and means for imparting to the tools 80 rubbing movements directed transversely of the line of stitches. 85

4. A machine of the class described having, in combination, a pair of rubbing tools relatively movable to receive the projecting edge portion of the sole of a shoe between them, resilient means for positioning said tools when idle with their opposed faces separated a distance less than the thickness 90 of the sole, the face of one of the tools being curved to permit the tools to be readily separated by inserting the sole between them, and means for operating the tools to rub 95 the sole. 100

5. A machine for operating upon turn shoes having, in combination, means for supporting the projecting edge portion of the sole of a shoe upon its upper face, and means for rubbing the lower face of said portion of the sole inwardly transversely of 105 the line of sole attaching stitches while the sole is thus supported, said rubbing means having a surface suitably extended to engage simultaneously with the edge portion that portion of the sole in which the sole attaching 110 stitches are located. 115

6. A machine of the class described having, in combination, a shoe beating tool, means for operating said tool to beat the side of a shoe, and means operated simultaneously with said tool to rub the upper and lower faces of the projecting edge portion of the sole of the shoe inwardly from the edge of the sole. 120

7. A machine of the class described having, in combination, a beating tool shaped for engagement with the side of a shoe from the welt crease upwardly, means for imparting to said tool rapid movements toward the side of the shoe in approximately parallel 125 130

relation to the plane of the sole, and a support arranged for continuous engagement with the bottom face of the projecting edge portion of the sole of the shoe to preserve the normal contour of the shoe bottom during the beating operation.

8. A machine of the class described having, in combination, a beater shaped for engagement with the side of a shoe from the 10 welt crease upwardly, means for operating said beater to beat the side of the shoe, and means movable with the beater for supporting the projecting edge portion of the sole of the shoe upon its bottom face to prevent 15 said portion from being distorted by the action of the beater.

9. A machine of the class described having, in combination, a beating tool shaped for engagement with the side of a shoe from 20 the welt crease upwardly, means for operating said tool to beat the side of a shoe, means for supporting the projecting edge portion of the sole of the shoe to prevent said portion from being distorted by the 25 action of the beating tool, and means for maintaining said supporting means and the beating tool in the same angular relation during the operation of said tool.

10. A machine of the class described having, in combination, a beating tool shaped for engagement with the side of a shoe from 30 the welt crease upwardly, means for operating said tool to beat the side of the shoe, means movable with the tool for supporting the projecting edge portion of the sole of the shoe upon its lower face during the beating 35 operation, and means for maintaining said supporting means and the sole in engagement under yielding pressure.

11. A machine of the class described having, in combination, a beating tool shaped for engagement with the side of a shoe from the welt crease upwardly, means for operating the tool to beat the side of the shoe, 45 the tool having also an end face shaped for rubbing engagement with the upper face of the projecting edge portion of the sole of the shoe, and means movable with the tool for maintaining said portion of the sole in 50 pressing engagement with the end face of the tool.

12. A machine of the class described having, in combination, a beating tool shaped for engagement with the side of a shoe from 55 the welt crease upwardly, means for operating the tool to beat the side of the shoe, the tool having also an end face shaped for rubbing engagement with the upper face of the projecting edge portion of the sole of the shoe during the beating operation, and means movable with the tool for rubbing simultaneously the lower face of the sole.

13. A machine of the class described having, in combination, a tool carrier, a pair 65 of relatively movable rubbing tools mounted

on said carrier and arranged to receive the projecting edge portion of the sole of a shoe between them, resilient means for moving one of said tools toward the other to press the sole between the tools, and means for operating the carrier to impart approximately right line movements to the tools.

14. A machine of the class described having, in combination, a tool carrier, a beating tool mounted on said carrier and shaped for engagement with the side of a shoe from the welt crease upwardly, means mounted on the carrier for supporting the projecting edge portion of the sole of the shoe upon its lower side during the beating operation, and means for operating the carrier to impart approximately right line movements to said tool and supporting means.

15. A machine of the class described having, in combination, a tool carrier, a beating tool mounted on said carrier and shaped for engagement with the side of a shoe from the welt crease upwardly, a support for the projecting edge portion of the sole of the shoe also mounted on said carrier, resilient means for maintaining the support and the sole of the shoe in pressing engagement during the beating operation, and means for operating the carrier to impart approximately right line movements to said tool and support.

16. A machine of the class described having, in combination, a tool carrier, a beating tool mounted on said carrier and shaped for engagement with the side of a shoe from 100 the welt crease upwardly, a support on the carrier arranged with reference to said tool for engagement with the lower face of the sole of the shoe during the beating operation, the beating tool being slidably mounted 105 for movement toward or from said support, resilient means for moving the tool toward the support, and means for oscillating said carrier.

17. A machine of the class described having, in combination, a shoe beating device and 110 a shoe rubbing device, and a common operating means for imparting movement to said devices, said devices being movable relatively to the operating means to bring one or the other device alternatively into position 115 to operate upon a shoe presented for treatment.

18. A machine of the class described having, in combination, a tool carrier comprising 120 an arm mounted for oscillatory movement, a tool head mounted on said arm, a beating tool on said tool head shaped for engagement with the side of a shoe from the welt crease upwardly about the forepart of 125 the shoe, and a second tool on the tool head shaped for similar engagement with the side of a shoe at the shank portion, the tool head being adjustable upon said arm to bring one or the other of the tools alternatively into 130

position to operate upon a shoe presented for treatment.

19. In a machine of the class described, a shoe shaping device having one portion 5 formed for engagement with the side of a shoe at the forepart from the welt crease upwardly and another portion at the same side of the device formed for engagement with a different part of the shoe, the two 10 portions of the device being disposed in separated relation to permit the projecting edge portion of the sole to be inserted between them, and operating means constructed to impart to said device approximately 15 right line movements toward a shoe presented for treatment.

20. A machine of the class described having, in combination, a beating tool shaped for engagement with the side of a shoe from the welt crease upwardly, means for operating said tool to beat the shoe, and means operated simultaneously with said tool to rub the lower face of the projecting edge portion of the sole inwardly from the edge, 20 said rubbing means being arranged to maintain continuous engagement with the projecting edge portion of the sole to support said portion during the beating operation.

25 In testimony whereof I have signed my name to this specification.

ORRELL ASHTON.
